Specification of Letters Patent.

Patented Aug. 7, 1917.

Application filed December 18, 1914. Serial No. 877,904.

To all whom it may concern:

Be it known that we, HENRY G. VOIGHT and GEORGE B. PICKOP, citizens of the United States, residing, respectively, in New Britain, Hartford county, and New Haven, New Haven county, Connecticut, have invented certain new and useful Improvements in Locks, of which the following is a full, clear, and exact description.

10 This invention relates to locks, and more particularly to corridor door locks of hotels, and similar buildings, although the invention is applicable to locks of other types.

For hotel use a lock is required which can 15 be opened at all times, and under all circumstances, by means of a special key known as an emergency key, which is usually kept in the possession of the proprietor or manager.

Moreover, in addition to the ordinary guest 20 or change keys, the locks of a hotel, or like building, may usually be operated by a master (maid's) key, a grandmaster key, and sometimes by a display key, the functions of which are well understood in the art.

25 Usually all of these various keys act on a single group of tumblers, *e. g.*, a series of pivoted tumblers, or a series of pin tumblers in a cylinder lock, and therefore the lock structure is more and more complicated as 30 the number of functions of the lock is increased, and at the same time the security factor is decreased very considerably by the large number of tumbler changes required.

The present invention relates to a lock 35 construction or arrangement in which these disadvantages are avoided, and wherein the emergency key, or other master key, for controlling the door, acts on a lock mechanism carried by, or housed in, the door frame or 40 casing. The lock mechanism on the door frame co-operates in such a manner with a bolt, or other like device on the door, as to provide an additional control of the door. The mechanism mounted on the casing or 45 door frame constitutes, in effect, an emergency attachment for the lock on the door, which may or may not be of the master keyed type, and access to the room can be gained at all times by the proprietor, whose 50 key will actuate the mechanism on the door frame in such a manner as to free the door and permit it to be opened merely by pushing or pulling on the same. Our present invention refers especially to lock mechanism of this general character in which the

locking device on the door is constituted by a latch bolt, or other yieldingly projected device, and one of the main objects which we have in view is the provision of simple, efficient means, operative by the emergency 60 key, for causing the release of the latch bolt from the strike or keeper.

Another object of the invention is to furnish a latch bolt lock having means to free or release the door by backward pressure on 65 the head of the latch bolt, which causes it to disengage the co-operating part of the strike.

The invention also has in view the general improvement in construction and operation 70 of devices of the class to which our invention relates.

In the accompanying drawings,

Figure 1 is a fragmentary outside elevation of a door and casing equipped with our 75 improvements,

Fig. 2 is a section on the irregular section line 2—2 of Fig. 1, showing the door locked,

Fig. 3 is a view similar to Fig. 2, with certain parts omitted, showing the door released by the emergency key,

Fig. 4 is a fragmentary view of the door casing, looking toward the face of the strike,

Fig. 5 is a fragmentary view, showing the emergency lock with the cap plate removed, 85 with the parts in position to lock the door,

Fig. 6 is a view similar to Fig. 5, showing the emergency lock in door-releasing position,

Fig. 7 is a detail section on line 7—7 of 90 Fig. 2, and

Fig. 8 comprises detail views of the change and emergency keys respectively.

In the particular embodiment of the invention which we have selected for illustration, the door is provided with an ordinary lock of the latch bolt type, having a fixed outer knob, and in which the latch bolt is adapted to be retracted from the outside by one or more keys of a suitable pin tumbler mechanism. The casing, or frame of the door, is provided with a strike plate having a part which may be moved to press back the latch bolt, by the actuation of an appropriate key called an emergency key, that operates an auxiliary, controlling, or emergency lock associated with the door frame. It will thus be seen that when the door is locked, the possessor of the emergency key may readily open it by pushing back the 100 105 110

latch bolt through the movable member associated with the strike, so that the bolt moves out of coöperation with the strike, and thereby access to the room can be gained, 5 in case of emergency or accident. When the movable part of the strike is again released to its normal position, the lock on the door will act in the usual way. The features spoken of above are not essential in all aspects of the invention, but they are mentioned to facilitate an understanding of the following description of the particular construction illustrated.

Referring to the drawings, A denotes the 15 door, B the door frame or casing, C the lock on the door, D the strike on the casing, E the auxiliary or emergency lock associated with the casing, and F the movable latch-actuating part controlled by said auxiliary 20 or emergency lock. The lock C is illustrated as of the mortise type, but this is unessential. It has a latch bolt 20, adapted to be retracted by one or more keys fitted to a pin tumbler cylinder lock 21, located in the 25 usual manner on the outer face of the door. In the particular form shown, the lock C is provided with the usual live inside knob 22 for retracting the bolt, and the knob 23 at the outside of the door is a fixed or 30 dummy knob, the retraction of the bolt from the outside being confined to the cylinder lock mechanism; but obviously, the outer knob 23 might be a latch-retracting knob adapted to be dogged by the usual movable 35 stop work.

Located in a suitable notch 24 in the stud 25 of the door frame is a U-shaped bracket 26, secured to the stud by means of screws 27^a. This bracket 26 forms a support or 40 carrier for the auxiliary lock E which is fitted within the intermediate part of the bracket, as shown in Figs. 4 and 5, and suitably secured to the bracket in such a position as to lie wholly within the notch, or 45 other cutaway part in the stud. At its lower part, the bracket is provided with an extension 27 which may extend completely across the notch in the stud, as shown, and which serves as a carrier for the movable latch-operating member F. Preferably, the latch-operating member F is of the pivoted type, being pivoted or swiveled to the extension 27 by means of the pivot pin 28 at a point below the auxiliary lock E. The lock E is 50 provided with a bolt 29, which carries a depending pin 30, extending out of the lock case through a slot 31 in the bottom thereof, and engaging an opening or socket 32, formed in the pivot member or arm F intermediate of the ends thereof. Thus, the 55 movable member F being pivoted to the bracket at 28, and being operatively connected with the bolt 29 will assume an inoperative position with respect to the latch bolt 60 20, when the bolt 29 is in the position shown

in Fig. 5, and will push the latch bolt clear of the strike D when the bolt 29 is moved to the position shown in Fig. 6. In other words, the bolt 29 of the auxiliary lock is adapted to hold the member F in an inoperative position with respect to the latch bolt, so that the latch bolt may take into the strike in the usual way; but when said bolt 29 is moved forward by its key 33, termed the emergency key, the member F will push the latch back from the locking position shown in Fig. 2 to the unlocking position shown in Fig. 3, so that the door may be opened from the outside merely by pushing on the same.

The auxiliary lock E, as previously stated, is located within the notch in the stud, so that when the covering or casing members of the door frame are applied, it will be securely housed in the interior of the casing. 85 In some cases, however, the emergency lock might be applied to the exterior of the casing. The outer casing member is shown at 34, the inner casing member at 35, and the intermediate casing member at 36, said last 90 named casing member being provided with the usual stop bead 37. Preferably, the lower and upper ends of the U-shaped bracket 26 will be mortised in the outer face of the stud and secured thereto, so that the 95 outer casing member 34 may then be applied in the usual manner.

By preference, the movable latch-operating member F will act on the latch bolt through the intermediary of a sliding plunger mounted in the pocket or box of the strike D. In the form shown, a hole is bored through the box part of the strike, and extending rearwardly from said hole or bore is a sleeve 38, suitably secured to the 100 strike. This sleeve and the opening in the strike proper, form in conjunction a guide for a plunger 39 movable depthwise of the strike, and having a head 40 to engage the forward edge of the latch bolt head, as 105 shown in Figs. 2 and 3. The head 40 is at the front or outer end of the plunger 39, and in the inoperative position of the plunger (Fig. 2), said head is preferably withdrawn in a counterbore 40^a in the box 110 of the strike, so as to clear the latch bolt head, and permit said bolt to engage the strike in the usual way. It will be obvious, moreover, that the head 40 limits the movement of the plunger in a rearward direction, that is, away from the head of the latch bolt. Movement of the plunger in an opposite direction is limited by a similar head 40^b on the rear end thereof, adapted to abut the sleeve 38. A screw 41 passes completely 115 through the plunger 40 and contacts at its rear end 41^a with a flat coöperating portion 41^b of the actuating member F. The screw 41 is provided with a nicked head, accessible from the face of the strike, so that by screw- 120

ing it in or out the throw of the plunger relative to the latch bolt may be suitably adjusted to a certain extent, as will be obvious.

A keyhole 42 for the auxiliary lock E passes through the outside casing member 34, and preferably a small escutcheon 42^a will be applied to said casing member around the keyhole. When the emergency key 33 is introduced into the lock E and turned in the proper direction, it releases a plurality of tumblers 43 from engagement with the stump or fence 44 on the bolt 29, and moves said bolt forward in its casing, with the result that the member F will move the plunger 39 forward, so that the latch bolt will be pressed back clear of the strike. The bolt 29 is normally held in its rearward position, corresponding to the inoperative position of the latch-actuating member F, by means of a spring 45. As the bolt 29 is moved forward, the stump or fence 44 passes into notches 46 of the tumbler gatings, and immediately upon the release of the key 33, the bolt will spring back to its initial position, thereby returning the member F to the inoperative position, corresponding to the locking position of the door. The emergency key is preferably of the drill pin type, as shown, and the key bit is prevented from making a full rotation in the keyhole by abutting a shoulder 47 on the bolt, so that the key cannot be turned to a position in which the bolt 29 is jammed back to hold the latch bolt out of the strike.

In Fig. 8, we have shown a key 48 adapted to the cylinder lock 21, and intended for use as a change key, or guest key. This particular key is, of course, of an absolutely different type from the emergency key 33, but the difference of type is not important so long as each key retains its own particular function. We have not shown an additional key or keys for the lock on the door, such for example, as a maid's master key, but such additional key or keys will obviously be provided if desired.

The operation of the improved lock mechanism will be obvious for the most part from the foregoing description. Under ordinary conditions, the strike acts in the customary manner, the plunger 39 and the arm F lying in the inoperative position shown in Fig. 2. Obviously, the latch bolt cannot be pressed back out of cooperation with the strike when the bolt member 29 is deadlocked by the tumblers 43 in the position shown in Fig. 5. Supposing, now, that the door of the hotel room is locked, with the guest inside, and the proprietor needs to gain access to the room, as in case of accident or emergency, he can immediately open the door by means of the emergency key 33, even if the key mechanism on the door has been deadlocked from the inside of the room (e. g., by a thumb

turn 22^a), in such a manner as to make the change, and other keys, inoperative on the latch bolt from the outside. By simply inserting the emergency key into the key-hole in the casing, and giving it a slight turn, 70 the latch bolt is pushed back out of engagement with the strike by means of the plunger 39, and the door can be opened at once by merely pushing on the same. On releasing the hold on the emergency key, the 75 spring 45, acting on the bolt 29, will immediately carry the member F back to its initial position, so that when the door is again closed the latch bolt can readily push back the plunger into an inoperative position, and 80 can enter in the opening in the strike in the usual manner, whereby the door is again locked. By our invention, both the lock on the door and the lock on the door frame can be made in the simplest form; thus in most 85 cases the two locks can be produced at a cost not appreciably greater than the cost of a single lock providing all of their combined functions. The security factor is very largely increased, because the emergency key 90 has its own group of tumblers, to which it can be specially adapted in order to avoid all liability of picking the emergency lock, and because the simplicity of the lock on the door, and the relatively small numbers of 95 keys adapted to said lock, tend to security and safety.

We have not attempted to illustrate and describe the various modifications in the details of the construction which may be 100 adopted within the scope of the invention as defined in the claims.

We do not claim broadly herein the combination of a lock on the door for locking the latter to the frame, a key for operating 105 said lock from the outside of the door, means for preventing the operation of said lock by said key, a second key, and means on the door frame operable by said second key for releasing the door from the frame 110 when said preventing means is in operative condition, as claimed in our application, Serial No. 877375, nor do we claim other features broadly claimed in that application.

What we claim is:

1. The combination with a door and door frame, of a bolt on the door for locking the door to the frame, a key for operating said bolt, means on the frame for pressing back said bolt into an inoperative position, and an emergency key for actuating said means; substantially as described.
2. The combination with a door and door frame, of a bolt on the door for locking the latter to said frame, a lock mounted on the frame, and means operatively connected with said lock for moving the bolt out of its bolting position with respect to said frame; substantially as described.
3. The combination with a door and door

frame, of a bolt on the door for locking the latter to said frame, a strike on the frame, a lock on the frame, means for operating said lock from the outside of the room, and 5 means operable by said lock for pushing the bolt out of the strike; substantially as described.

4. The combination with a door and door frame, of a bolt on the door for locking the latter to said frame, a strike on the frame to receive said bolt, a lock on the frame comprising a case, a bolt therein, and a tumbler for said bolt, a key for said lock adapted to operate said last-named bolt, and means operable by said last-named bolt for pushing the first bolt out of the strike; substantially as described.

5. The combination with a door and door frame, of a lock on the door having a latch bolt, a strike plate fixed to said frame to receive said latch bolt, said frame having a keyhole therein, a key insertible into said keyhole, and means operative by said key for pushing said bolt clear of said strike plate; 25 substantially as described.

6. The combination with a door and door frame, of a lock on the door having a latch bolt, a strike plate on the frame to receive said latch bolt, a change key operating in a 30 keyhole in the door for retracting said latch bolt, a tumbler controlled member on the door frame for pushing said latch bolt out of the strike, and an emergency key for operating said tumbler controlled member; 35 substantially as described.

7. The combination with a door and door frame, of a lock on the door having a latch bolt, key mechanism associated with said lock for retracting said latch bolt, a strike 40 on the door frame to receive said bolt, a lock mounted on the frame and comprising a case, a bolt therein, and a tumbler for said bolt, a key to coöperate with said tumbler and actuate said last-named bolt, said key operating 45 in a keyhole on the door frame, a lever connected with the bolt of said second lock to be shifted thereby, and means interposed between said lever and the latch bolt for pushing the latter out of the strike by the rotation of said key; substantially as described.

8. The combination with a door and door frame, of a lock on the door having a bolt, a strike or keeper on the frame to receive said bolt, a change key for withdrawing said bolt from said strike, said change key operating in a keyhole in the door, means for preventing the retraction of said bolt by means of said key, an emergency key, and means on the door frame operative by said 55 emergency key for retracting said bolt from said strike or keeper when said preventing means is in operative condition; substantially as described.

9. The combination with a door and door frame, of a lock on the door having a bolt, 65

a strike or keeper on the door frame to receive said bolt, a change key for retracting said bolt from said strike, said change key operating in a keyhole at the outside of the door, means for preventing the retraction of said bolt by said change key, an emergency key, a tumbler controlled member on the door frame operative by said emergency key, and means operative by said tumbler controlled member for moving said bolt out 70 of the strike when said preventing means is in operative condition; substantially as described.

10. The combination with a door and door frame, of a lock on the door having a bolt, a strike or keeper fixed to the frame for receiving said bolt, a change key for retracting said bolt from said strike or keeper, an emergency key insertible in a keyhole in the door frame, a tumbler controlled bolt operative by 75 said emergency key and housed within the door frame, and a plunger for pushing said first-named bolt out of the strike or keeper operative by said tumbler controlled bolt; 80 substantially as described.

11. The combination with a door and door casing, of a lock on the door having a latch bolt, a strike on the door casing to receive said latch bolt, a change key insertible in a keyhole on the door for retracting said 90 latch bolt, a lock mortised in the door casing adjacent said strike, and including a tumbler-controlled bolt, an emergency key insertible in a keyhole in the door casing for operating said tumbler-controlled bolt, a 95 member connected with said tumbler-controlled bolt to be shifted thereby, and a plunger in the strike for pushing the latch bolt out of the strike, adapted to be operated by said last-named member; substantially as 100 described.

12. The combination with a door and door frame, of a lock on the door having a bolt, a strike or keeper fixed to the frame for receiving said bolt, a change key for retracting said bolt from said strike or keeper, an emergency key insertible in a keyhole in the door frame, a tumbler controlled bolt operative by said emergency key and housed within the door frame, and a plunger for 110 pushing said first-named bolt out of the strike or keeper operative by said tumbler controlled bolt, said plunger adjustable with respect to the bolt on the door; substantially as described.

13. The combination with a door and door casing, of a lock on the door having a latch bolt, a strike on the door casing to receive said latch bolt, a change key insertible in a keyhole on the door for retracting said latch 125 bolt, a lock mortised in the door casing adjacent said strike, and including a tumbler-controlled bolt, an emergency key insertible in a keyhole in the door casing for operating said tumbler-controlled bolt, a member con- 130

5 nected with said tumbler-controlled bolt to be shifted thereby, a plunger in the strike for pushing the latch bolt out of the strike, adapted to be operated by said last-named member, and a spring acting on said tumbler-controlled bolt to normally hold it in such a position that the latch bolt may enter the strike; substantially as described.

10 14. An emergency attachment for locks, comprising a strike, a lock, and a movable bolt-actuating member coöperating with said strike and lock, and connected with said lock to be shifted thereby; substantially as described.

15 15. An emergency attachment for locks, comprising a strike, a movable bolt-actuating member coöperating with said strike, a lock operatively connected with said member, and a key for operating said lock; substantially as described.

20 16. An emergency attachment for locks, comprising a strike or keeper, a bolt-actuating plunger movable through said strike or keeper, a lock operatively connected with said plunger to move the same, and a key for operating said lock; substantially as described.

25 17. The combination with a door having a latch bolt thereon, of a door frame having a notch therein, a lock mounted in said notch, casing members inclosing said lock, a key insertible into said lock through one of said casing members to actuate said lock, a strike or keeper on the door frame to receive said latch bolt, and a member mounted in said strike or keeper and shiftable by the operation of said lock to push said bolt out of said strike or keeper; substantially as described.

30 18. The combination with a door and door frame, of a bolt on the door for locking the latter to the frame, a change key for operating said bolt from the outside of the door, means operable from the inside of the door for preventing the retraction of the bolt by means of said change key, an emergency key, and means on the door frame, operable by said emergency key, for pushing said bolt out of locking position with respect to said frame; substantially as described.

35 19. The combination with a door and door frame, of a lock on the door having a bolt, a strike on the frame adapted to be engaged by said bolt, a change key for operating said bolt from the outside of the door, means operable from the inside of the door for preventing the retraction of said bolt by said change key, an emergency key, and means on the door frame, operable by said emergency key, to shift the bolt into releasing position with respect to said strike; substantially as described.

40 20. The combination with a door and door casing, of a bolt on the door for locking the latter to said casing, a lock housed in said

casing, a key for actuating said lock, and means operable by said lock for pushing said bolt back into an inoperative position, said means adjustable in its throw; substantially as described.

45 21. The combination with a door and door frame, of a latch bolt on the door, a strike on the frame, a lock on the frame, a key for said lock, and means operable by said lock for pushing said bolt out of the strike, said pushing means being adjustable with respect to the bolt; substantially as described.

50 22. The combination with a door and door frame, of a latch bolt on the door, a strike on the frame to receive said latch bolt, a key for operating said bolt to retract the same, means on the frame for pressing said latch bolt out of the strike into an inoperative position, and an emergency key operable from the outside of the door in a keyhole in the door frame for actuating said last-named means; substantially as described.

55 23. The combination with a door and door frame, of a latch bolt on the door, a strike on the door frame, a key insertible into a keyhole in the door for retracting said latch bolt, a tumbler-controlled bolt on the door frame, means operable by said tumbler-controlled bolt to press said latch bolt out of the strike, and an emergency key for operating said last means from the outside of the door; substantially as described.

60 24. The combination with a door and door frame, of a lock on the door having a bolt, a strike plate fixed on the frame to receive the bolt, a change key to operate said bolt, an emergency key, and an emergency mechanism on the door frame, operable from the outside of the door by said emergency key for withdrawing said bolt from said strike plate.

65 25. The combination with a door and door frame, of a bolt on the door, a keeper on the frame to receive said bolt, and tumbler controlled means operable from the outside of the door and located on the door frame for moving said bolt out of said keeper.

70 26. The combination with a door and door frame, of a bolt on the door, a keeper on the frame to receive said bolt, a change key operable in a key hole on the door for actuating said bolt, tumbler-controlled emergency mechanism mounted on the door frame for moving said bolt out of said keeper, and an emergency key operating in a key hole on the door frame at the outside of the room for actuating said emergency mechanism.

75 27. The combination with a door and door frame, of a bolt on the door for locking the latter to said frame, and tumbler-controlled, key actuated mechanism on the frame for moving said bolt into an inoperative position.

80 28. The combination with a door and door frame, of a bolt on the door for locking the

latter to said frame, and tumbler-controlled, key actuated mechanism on the frame for moving said bolt into an inoperative position from the outside of the room.

29. The combination with a door and door frame, of a bolt on the door for locking the latter to said frame, a keeper on the frame, said frame having a key hole at the outside of the room, an emergency key insertible into said key hole, and tumbler-controlled means within the door frame operable by

said emergency key to push said bolt out of said keeper.

In witness whereof, we have hereunto set our hands on the 16th day of December, 1914.
